UNITED STATES PATENT OFFICE.

HENRY H. McLAUCHLIN, OF KNOXVILLE, TENNESSEE.

FUSE.

1,198,364.

Specification of Letters Patent. Patented Sept. 12, 1916.

Application filed June 29, 1915. Serial No. 37,047.

To all whom it may concern:

Be it known that I, HENRY H. McLAUCHLIN, a citizen of the United States, residing at Knoxville, in the county of Knox and State of Tennessee, have invented new and useful Improvements in Fuses, of which the following is a specification.

This invention relates to improvements in fuses and has particular application to 10 a fuse of the cartridge type.

In carrying out the present invention, it is my purpose to provide a cartridge fuse wherein the fusible element may be readily and quickly inspected whenever desired so 15 that the condition of such element may be determined and wherein the fusible element may be quickly and conveniently replaced whenever necessary.

It is also my purpose to provide a cartridge fuse wherein the component parts may be readily disassembled whenever it is desired to replace the fusible element and wherein the parts will be so arranged and correlated as to reduce the possibility of de- 20 arrangement to a minimum.

With the above and other objects in view, the invention consists in the construction, combination and arrangement of parts hereinafter set forth in and falling within the 25 scope of the claim.

In the accompanying drawing, Figure 1 is a view in side elevation of a cartridge fuse constructed in accordance with the present invention. Fig. 2 is a longitudinal sectional 30 view therethrough. Fig. 3 is a cross sectional view through the same. Fig. 4 is a perspective view of one of the fuse holding jaws removed from the cartridge. Fig. 5 is a perspective view of the shell. Fig. 6 is 35 a view in side elevation showing a modified form of cartridge. Fig. 7 is a perspective view of a modified form of fusible element.

Referring now to the drawing in detail, 1 designates a shell semicircular in cross section and having the ends thereof formed 40 with circular retaining bands 2 coaxial with the shell 1.

3, 3 indicate the fuse holders, each comprising a circular body 4 formed with a 45 threaded bore 5 and having one end portion formed with a transverse way 6 and a slot 7 contiguous to the way and opening onto the adjacent extremity of the body. The side walls of the slot 7, at one end of the latter, are cut away slightly as at 8 to provide 55 a recess, while formed on the outer surface

of the body 4 at opposite sides of the slot 7 are lugs 9 forming diametrically opposed shoulders 10 and abutments 11. The bodies 4 of the holders 3 are placed in the shell 1 60 and the shoulders 10 engage the longitudinal edges of the shell, while the ends of the bodies remote from the lugs 9 are adapted to slide into the bands 2 and as the bodies are slid into the respective bands the abutments 11 engage the inner edges of the bands to limit the movement of the holders into the bands and expose the ways 6. Loosely surrounding the shell 1 is a tubular sleeve 12 formed with a longitudinal slot 13 70 adapted to be moved into and out of registration with the open side of the shell and loosely surrounding the ends of the sleeve 12 respectively are caps 14 formed with inwardly projecting threaded studs 15 engaging in the bores 5 in the bodies of the respective holders so as to hold the holders at the respective ends of the shell 1 and prevent longitudinal movement of the sleeve 12 along the shell. 75

16 designates a fusible element having the end portions thereof bent at right angles to the central portion and disposed within the ways 6 in the respective holders 3, the central portion of the fusible element at the juncture with the bent ends engaging the recesses formed by the cut-away portions 8. 80

In practice, the holders are placed in the shell and the ends of the fusible element disposed within the ways in the holders, as just 85 described. The sleeve 12 is now slipped over the shell and the slot in the sleeve brought into registration with the open side of the shell. The fingers of the operator may be passed through the slot in the open side of the shell and engaged with the holders to hold the latter in the respective ends of the shell. Caps are now placed upon the ends 90 of the sleeve and the studs 15 threaded into the bores in the holders, the operator's fingers holding the holders in position to receive the studs. As the studs are threaded into the bores in the respective holders the inner ends of such studs bind against the right angular ends of the fusible element, thereby securely holding the latter within the shell while the caps are drawn onto the ends of the sleeve to prevent longitudinal movement of the sleeve relatively to the shell and when the caps are tightened the 95 sleeve is held against rotary movement around the shell. When desired, the sleeve 100

105

110

may be rotated around the shell to move the slot 13 in the sleeve into and out of registration with the open side of the shell.

In the modified form of cartridge shown 5 in Fig. 6, the tubular sleeve 12 entirely surrounds the shell and is minus the slot 13 and when it is desired to renew the fusible element, the caps are removed from the ends of the sleeve and the shell withdrawn 10 from the sleeve.

The fusible element shown in Fig. 7 is in the form of a link and is composed of suitable fusible metal shaped to form a flat ribbon or link. The ends of this ribbon or 15 link are thickened to form transversely extending lugs 17. In the use of this link or ribbon, the lugs 17 are inserted in the ways 6 in the respective holders, while the portions of the ribbon adjacent to the lugs lie 20 within the slots 7.

While I have herein shown and described certain preferred forms of my invention by way of illustration, I wish it to be understood that I do not limit or confine myself 25 to the precise details of construction herein described and delineated, as modification

and variation may be made within the scope of the claim without departing from the spirit of the invention.

I claim:

A cartridge fuse comprising a shell having an open side, fuse holders in said shell adjacent to the respective ends thereof, a sleeve surrounding said shell and having an elongated slot formed therein and movable to bring said slot into and out of registration with the open side of said shell, caps closing the ends of said sleeve and shell, a fusible element within said shell and having the ends thereof engaged in said holders, and studs integral with said caps and threaded into said holders to hold the latter in said shell, and engaging the ends of said fusible elements to clamp the latter in said holders.

In testimony whereof I affix my signature in presence of two witnesses.

HENRY H. McLAUCHLIN.
